UNITED STATES PATENT OFFICE.

GUSTAV ADOLPH AND ALBERT PIETZSCH, OF MUNICH, GERMANY.

MANUFACTURE OF PERSULFATES.

1,059,809.

Specification of Letters Patent.

Patented Apr. 22, 1913.

No Drawing.

Application filed October 6, 1910. Serial No. 585,571.

To all whom it may concern:

Be it known that we, GUSTAV ADOLPH and ALBERT PIETZSCH, citizens of Germany, residing at Munich, Bavaria, Germany, have 5 invented certain new and useful Improvements in the Manufacture of Persulfates; and we do hereby declare the following to be a full, clear, and exact description of the invention, such as will enable others skilled 10 in the art to which it appertains to make and use the same.

This invention relates to the manufacture of persulfates of the alkali-metals, and the same is based on the utilization of persulfate of ammonium, such as can be readily obtained by electrolytic methods, for this purpose. In this art, the production of potassium-persulfate is at present carried out either by directly preparing the same 15 electrolytically, or by the conversion of ammonium-persulfate. The latter method has the advantage that it takes as a starting product ammonium-persulfate which is readily obtainable by electrolytic methods, 20 while the potassium-persulfate can only be obtained with difficulty and with very poor yields. A disadvantage of the said method of starting with ammonium-persulfate, however, resides in the fact that the ammonium-persulfate is reacted on by potassium-carbonate, a very costly reagent, and that there 25 after the ammonium-sulfate must be regenerated from the ammonium carbonate by the aid of sulfuric-acid.

30 The object of the present invention is to overcome the difficulty above pointed out, and with this object in view, the applicants have devised the present invention which is based on the discovery made by them, that potassium-persulfate may be directly obtained 35 from the sulfates of potassium, under which term are to be understood not only the neutral sulfates but other sulfates, such as bisulfate of potassium, said reaction proceeding according to the equations:

50 In this manner, the ammonium-persulfate

may be readily and simply converted into persulfate of potassium, a sulfate-of-ammonium solution being obtained as one of the by-products of the reaction, from which 55 an ammonium-persulfate solution may be readily obtained electrolytically directly or with the addition of sulfuric-acid. From this it will be seen that the manufacturer has it in his power to regenerate the ammonium-persulfate continuously during the 60 process and as the same is required.

Under the present invention potassium persulfate is directly obtained from potassium sulfate with as advantageous a utilization 65 of the electric current as in the case where ammonium persulfate is obtained from ammonium sulfate. This new process is based on the fact that, as applicants have found, solutions of ammonium persulfate 70 which has been obtained by known electrolytic methods, may be directly acted on by sulfate of potassium in solid form and undissolved, in such a way that an ammonium sulfate remains in the solution.

75 The following example is given for the purpose of fully disclosing the invention:

Example 1: To an ammonium-persulfate solution obtained electrolytically, there is added an equivalent amount of potassium-sulfate or of potassium-bisulfate in a powdered or solid form, the mixture being 80 vigorously agitated and gently heated. The potassium-persulfate is immediately separated from the solution in the form of fine 85 crystalline laminæ or plates, and may be separated by the usual methods, such as siphoning off liquid, by decanting, centrifugal action, or otherwise. The remaining solution of ammonium-sulfate, either in the 90 neutral form or as bisulfate, can then be regenerated to ammonium-persulfate by subjecting the same to electrolysis.

The applicants have further found that the conversion of ammonium-persulfate to 95 potassium-persulfate can be carried out to particular advantage when this is done in connection with the electrolytic action in the electrolyzer, for which purpose a mixture of ammonium-sulfate and potassium-sulfate, 100 under which terms are to be understood either the neutral or bisulfates, is directly

utilized. Under these conditions, the ammonium-persulfate is formed at the anode with the usual good yields, amounting to 80% and upward. This freshly generated 5 ammonium-persulfate is, however, immediately and at the moment of its formation converted into potassium-persulfate and ammonium-sulfate by the reaction of the potassium-sulfate existing in the bath or solution. 10 The potassium-persulfate thus formed is thrown out in solid form and the ammonium-sulfate is then again converted into the persulfate, under the action of the current. Under this method of proceeding, it 15 is, therefore, only necessary to supply the potassium-salt as fast as it is consumed, by additions of further quantities of potassium-sulfate (neutral or bisulfate) in order to obtain a continuous uninterrupted production 20 of potassium-persulfate with high yields. A very great advantage in this connection is, that the process may be carried out without the intervention of a diaphragm, for the reason that practically no persulfate remains in 25 solution. The following example will serve to more fully disclose this modification of the process.

Example 2: A solution of 200 grams of ammonium-bisulfate together with 400 30 grams of potassium-bisulfate is subjected to electrolysis in the usual manner with the aid of platinum electrodes and without the intervention of a diaphragm, the electrolyte remaining constantly in contact with solid 35 potassium-bisulfate. Under this treatment solid potassium-persulfate is thrown down in the bath while ammonium-bisulfate goes into solution. This process may be carried out with a yield of from 80% at the anode, 40 while the reduction does not exceed more than 1 to 2%. A surprising discovery made by these applicants in this connection is, that by the same treatment sodium-persulfate, a body which has been very difficult 45 to obtain heretofore, being very readily soluble, can be obtained with ease. Hitherto this salt could not even be obtained with the aid of carbonate of sodium from ammonium-persulfate; it was necessary for this 50 purpose to employ caustic soda or sodium-hydrate, the escaping ammonia under this treatment having been absorbed with sulfuric-acid. The applicants have found that by using the same method as above described, the ammonium-persulfate may be readily converted into sodium persulfate, leaving as a by-product ammonium-sulfate, by treating the said ammonium-persulfate with sodium-sulfate (neutral or bisulfate). 55 Here again, the conversion may be carried out concurrently with the electrolysis with particular advantage. However, in this case, in view of the ready solubility of sodium-persulfate, the two electrodes must

be separated by a diaphragm. After the 65 electrolyte has been saturated with sodium-persulfate, the latter begins to be precipitated, the sodium-salt thus precipitated being replaced by sodium-bisulfate. In order to more fully disclose this process the following example may serve:

Example 3: A solution of 500 grams sodium-bisulfate together with 500 grams ammonium-bisulfate is subjected to electrolysis in a diaphragm electrolyzer provided with 75 platinum electrodes, sodium-bisulfate being continually supplied to the anode space as the reaction proceeds, while the gases escaping from the cathode space are carried over into anode solution for the purpose of 80 absorbing any ammonia which might escape from the acid anode solution. After a period of time, sodium-persulfate begins to be precipitated in the anode space. The yield under this process attains about 80%. 85

It will be noted that the term sulfates as employed in the claims includes not only the neutral sulfates but also the bisulfates.

What we claim and desire to secure by Letters Patent is as follows:

1. The process of obtaining a persulfate of an alkali-metal, which consists in causing a sulfate of said alkali-metal in an undissolved state to react on a bath of ammonium persulfate.

2. The process of obtaining a persulfate of an alkali-metal, which consists in mixing ammonium sulfate in a bath with a sulfate of an alkali-metal and subjecting the bath to electrolysis.

3. The process of obtaining a persulfate of an alkali-metal, which consists in subjecting a bath containing ammonium sulfate and a sulfate of said alkali-metal to electrolysis, and adding fresh supplies of alkali-metal sulfate as the conversion of the alkali-metal sulfate into the persulfate proceeds, to reconvert persulfate of ammonium into the sulfate.

4. The process of obtaining a persulfate 110 of an alkali-metal, which consists in subjecting a bath containing ammonium sulfate and undissolved alkali-metal sulfate to electrolysis, and adding fresh supplies of solid alkali-metal sulfate as the electrolysis 115 proceeds, to reconvert persulfate of ammonium into the sulfate.

5. The process of obtaining potassium-persulfate, which consists in causing a sulfate of potassium in an undissolved state 120 to react on a solution of ammonium-persulfate.

6. The process of obtaining potassium-persulfate, which consists in subjecting a bath containing a potassium-sulfate and ammonium-sulfate to electrolytic action.

7. The process of obtaining potassium-persulfate, which consists in subjecting a

bath containing potassium-sulfate and ammonium sulfate to electrolytic action, and adding fresh supplies of potassium sulfate to the bath as the reaction proceeds to 5 convert persulfate of ammonium to the sulfate.

In testimony whereof we hereunto affix

our signatures in the presence of two witnesses.

GUSTAV ADOLPH.
ALBERT PIETZSCH.
